UNITED STATES PATENT OFFICE.

WILLIAM OREM, OF BALTIMORE, MARYLAND.

DESIGN FOR A BOTTLE-STOPPER.

48,735.

Specification for Design.

Patented Mar. 14, 1916.

Application filed January 3, 1916. Serial No. 70,039. Term of patent 7 years.

To all whom it may concern:

Be it known that I, WILLIAM OREM, a citizen of the United States, residing in the city of Baltimore, in the State of Maryland, have invented a new, original, and ornamental Design for Bottle-Stoppers, of which the following is a specification, reference being had to the accompanying drawing, forming part thereof.

Figure 1 is an elevation of a bottle stop-

per, showing my new design. Fig. 2 is a bottom plan view thereof.

I claim:

The ornamental design for a bottle stopper, as shown.

WM. OREM.
